UNITED STATES PATENT OFFICE.

WAYNE S. SEARLES, OF PROVIDENCE, RHODE ISLAND, ASSIGNOR TO UNIVERSAL OPTICAL CORPORATION, OF PROVIDENCE, RHODE ISLAND, A CORPORATION OF RHODE ISLAND.

EYEGLASS MOUNTING.

Application filed April 26, 1922. Serial No. 556,594.

To all whom it may concern:

Be it known that I, WAYNE S. SEARLES, a citizen of the United States, residing at Providence, in the county of Providence and State of Rhode Island, have invented certain new and useful Improvements in Eyeglass Mountings, of which the following is a specification.

This invention relates to improvements 10 in eyeglass or spectacle mountings, and has for its object to provide in such a mounting a spring-pressed guard member having a bearing-collar about its pivot opening, a sleeve being mounted in said opening having 15 an enlarged spring bearing portion above the collar so that the upper coil of the spring which is practically supported against rotation is in contact therewith and a pivot post being arranged to extend 20 through the sleeve and be secured in the bridge portion of the mounting.

With these and other objects in view, the invention consists of certain novel features of construction, as will be more fully described, and particularly pointed out in the appended claims.

In the accompanying drawings:

Figure 1 is a side elevation partly in section showing a portion of an eyeglass frame 30 with my improved construction for the support of the spring mounted thereon.

Figure 2 is a top view sectioned just under the head of the pivot post.

Figure 3 is a side elevation of the sleeve 35 which embraces the post and extends down inside of the collar on the guard-member.

Figure 4 is a view showing a modified construction of pivot post receiving sleeve mounted in operative position.

Figure 5 is a sectional elevation of the 40 modified form of sleeve detached.

It is found in practice in the construction of eyeglass mountings of this character that where all of the coils of the guard-operating 45 spring bear directly against the fixed post that the lower coils which are constantly moving due to the opening and closing actions of the guard members, works against the post and the friction soon wears off the 50 gold plate of the wire and destroys the action of the spring.

Then again it is found to be of advantage structurally, to draw this collar only to a height to receive but a portion of the 55 coils of the spring and to provide an addi-

tional bearing surface for the upper coils which I have accomplished by the provision of a sleeve having an enlarged portion of a diameter substantially equal to that of the collar, and the following is a detailed description of one means by which this result may be accomplished:—

With reference to the drawing, 10 designates the usual guard member which is provided at one end with the usual nose-piece 60 11 and at its opposite end with a finger-engaging portion 12 and near its center it is provided with a pivot-receiving opening 13 about which I have drawn up the material from the plane of the stock providing 65 a collar 14 of a height equivalent to a predetermined number of superimposed coils of the helical spring 15 which in this particular instance is sufficient to receive three 70 coils of the four-coiled spring. 75

By drawing up this collar from the stock to this particular height the same may be accomplished by a single drawing operation while two or more drawing operations would be necessary to extend the collar another 80 twenty-five (25) per cent higher.

Then again this member is adapted to be pivotally mounted upon the saddle portion of the bridge 16 and in this collar portion I have mounted a sleeve-member 17 having 85 an enlarged portion 18 at its upper end, having an outer diameter substantially the same as the collar 14, its enlarged portion being of a width equaling substantially that of the diameter of one of the coils of the 90 wire spring which surrounds it.

In order to pivotally mount this finger-piece mounting upon the bridge member, I have provided a pivot-post 19 screw threaded at its lower end 20 into the bridge-member 95 and this post is provided with an enlarged head 21 above the sleeve to hold the whole in place.

By my improved construction which provides for the sleeve 17, I am enabled to 100 employ the standard or stock screw 19 to serve as a pivot post and the sleeve with the enlarged head serves to fill in the space between the upper end of the collar 14 and the head, to provide room for the upper coil 105 of the spring, the shank portion of the sleeve serving as an elongated bearing to prevent excessive wear by the rotation of the sleeve in the collar and on the post.

The device is extremely simple and prac- 110

tical in construction and by its use the necessity of drawing the collar on the finger piece to the full height necessary to receive all of the coils of the spring, is obviated.

5. In some instances instead of forming the collar portion 18 in the sleeve 17 and positioning the sleeve inside of the collar on the guard member I place the sleeve on the outside of the collar and form the enlargement 10 on the inside of the sleeve as at 22, see Figures 4 and 5, which enlargement or thickened portion also serves to fill the space between the top of the collar 14 and the head 21 of the pivot post 19.

15. The foregoing description is directed solely towards the construction illustrated, but I desire it to be understood that I reserve the privilege of resorting to all the 20 mechanical changes to which the device is susceptible, the invention being defined and limited only by the terms of the appended claims.

I claim:

1. In an eyeglass mounting, the combination 25 with a pivotally mounted spring-pressed guard member having a bearing collar about its pivot opening, a sleeve extending through said collar and having a spring-bearing portion above said collar, a pivot 30 post extending through said sleeve, and a spring coiled about said collar and sleeve, its sleeve engaging end being relatively fixed

against rotation and the opposite end of the spring being connected to said guard to move therewith.

35

2. In an eyeglass mounting, the combination with a pivotally mounted spring-pressed guard-member having a bearing collar about its pivot opening, a sleeve extending through said collar, and having a spring 40 bearing portion above said collar of a diameter substantially that of the outer surface of said collar, a pivot post extending through said sleeve, and a spring coiled about said collar and sleeve having its upper end fixed and its lower end positioned 45 to act upon said guard.

45

3. In an eyeglass mounting, the combination with a body member, a pivotally mounted spring-pressed guard member having a bearing collar about its pivot opening, a pivot post extending through said collar having a head at one end spaced above said collar, the other end of said post being threaded into said bridge, a sleeve surrounding said post and having a thickened wall portion filling the space between the top of said collar and post head, a pivot post extending through said sleeve, and a spring 60 coiled about said collar and sleeve having its upper end fixed and its lower end positioned to act upon said guard.

55

In testimony whereof I affix my signature.
WAYNE S. SEARLES.
